(57) **CLAIM**

The ornamental design for a light-emitting diode, as shown and described here.

DESCRIPTION

FIG. 1 is a perspective view of the light-emitting diode in accordance with my new design, showing an upper surface and side surfaces thereof as viewed from diagonally above;

FIG. 2 is a perspective view thereof, showing a bottom surface and side surfaces thereof as viewed from diagonally above;

FIG. 3 is a front elevation view thereof;

FIG. 4 is a rear elevation view thereof;

FIG. 5 is a top plan view thereof;

FIG. 6 is a bottom plan view thereof;

FIG. 7 is a left side elevation view thereof, (a right side view being a mirror image thereof); and,

FIG. 8 is a cross-sectional view taken along line 8 in FIG. 5. The article is a light-emitting diode (LED) including two resin-sealed portions, each sealing at least one LED element, and at least one of the two resin-sealed portions includes at least one fluorescent material.
